UNITED STATES PATENT OFFICE.

OTTO W. SCHAUM, OF PHILADELPHIA, PENNSYLVANIA.

BALL-GRINDING MACHINE.

1,252,366.

Specification of Letters Patent.

Patented Jan. 1, 1918.

Application filed May 26, 1917. Serial No. 171,280.

To all whom it may concern:

Be it known that I, OTTO W. SCHAUM, a citizen of the United States, and a resident of Philadelphia, county of Philadelphia, 5 State of Pennsylvania, have invented new and useful Improvements in Ball-Grinding Machines, of which the following is a specification.

The invention relates to machines for 10 grinding balls and particularly to machines in which the balls while being operated upon by an abrading wheel are supported by or rest upon spaced ball-supporting rings against which the balls are pressed by a rotating ball-revolving ring.

In machines of this type that portion of the ball which is to be operated upon is forced through the space between the ball-supporting rings by the ball-revolving ring 20 and is acted upon by the abrading-wheel which is on the opposite side of the spaced supporting rings from that upon which is located the ball-revolving ring or ball-pressing ring as it is frequently called.

The machine which is the basis of the 25 present invention is of the vertical type, to wit, of the type in which the ball-revolving ring and the abrading-wheel each revolves about its own vertically extending axis. In 30 the machine shown the spaced ball-supporting rings are concentric with each other and one of these rings is frequently referred to as the outer ball-supporting or outer segment ring and the other of these rings is frequently referred to as the inner ball-supporting or inner segment ring.

In machines of this type it is desirable to 40 have these segment rings firmly held in respect to each other and in the construction shown this is accomplished by supporting the inner segment ring on a carrier that can be secured to and is concentric with a carrier upon which the outer segment ring is located. The carrier for the inner segment 45 ring can be moved vertically at will so as to raise and lower the inner segment ring. The ball-pressing ring is also secured to an intermediate carrier which is revolvably mounted on one of the segment ring carriers, preferably upon the inner segment ring carrier, and the construction is such that the intermediate carrier can be raised and lowered at will. The abrading-wheel is also mounted so that it can be readily raised and lowered 55 at will.

In carrying out the grinding operation and particularly in the grinding of comparatively small balls, it is advisable to place a row of balls on the ball-supporting rings, prior to performing the grinding operation, 60 to perform the operation when the balls are in this position, to remove the balls when ground and to supply a new lot or charge of balls for a succeeding grinding.

The machine which is the basis of the 65 present invention is constructed so that balls can be supplied thereto and removed therefrom in the manner just described, although it is to be understood that the invention is not necessarily limited to a machine in 70 which the balls are supplied and removed in said manner, as there can be readily applied to the machine a means for successively feeding the balls into operative position through a feeding trough and a means for 75 successively ejecting the balls being ground and for delivering the same from the machine. A feeding means and an ejecting means for this purpose are well known in the art. 80

The invention is directed to the features above referred to and to other features of construction, as will be hereinafter more clearly pointed out.

As illustrating a specific manner in which 85 the invention may be realized reference is made to the accompanying drawings forming a part of this specification and in which drawings,

Figure 1 is a vertical view of a ball grinding machine partially in section.

Figs. 2 to 6 inclusive illustrate the different positions the spaced segment rings, ball-pressing ring and the abrading-wheel may assume relative to each other; in other 95 words, these views illustrate the position which the parts may occupy from the time when the lot of balls is placed on the machine until said lot has been discharged from the machine and another lot substituted 100 therefor for a succeeding grinding operation.

Figs. 7 and 8 are, respectively, plan and side views of a portion of the mechanism which is employed in the raising and lowering 105 of the abrading-wheel.

The reference character 1 designates the main frame of the machine which is a vertically extending frame. A carrier 2 is connected to or carried by the upper end of 110

this main frame. A ball-supporting or segment ring 3 is secured to the carrier at the lower end thereof and this carrier is frequently referred to as the outer carrier since 5 the outer segment ring is secured to or carried by it. An inner ball-supporting ring or segment ring 4 is concentric with the outer ring 3 but spaced therefrom and the rings 3 and 4 constitute the spaced ball-supporting or segment rings. A ball-revolving ring, or ball-pressing ring 5 as it is frequently called, engages a row of balls 6 when on the spaced segment rings and forces the balls against said segment rings 10 so that a portion of each ball extends through the space between said segment rings whereby the balls can be engaged by the abrading-wheel 7, when in normal operative elevated position. The normal operative position of this wheel 7 is indicated in 15 Figs. 2 and 6. The inner segment ring 4 is carried by a spindle or shaft 8 by being secured to the lower end of the latter. This spindle or shaft 8 may be considered as a part 20 of an inner carrier 9 the function of which inner carrier is to firmly maintain the inner segment ring 4 in operative position in respect to the outer segment ring 3. The inner carrier 9 may also be considered to comprise 25 a bushing or sleeve 10 although in many respects this bushing or sleeve 10 might be considered as an adjustable part of or on the outer carrier 2, dependent upon the particular view taken. Upon the bushing 10 30 there is revolvably mounted an intermediate carrier 11 to which there is connected the ball-pressing ring 5 through the medium of an annular ring 12 and bolts 13. A resilient means as 14 may be provided between the 35 underside of a flange 15 of the intermediate carrier and the annular ring 12 to which the ball-pressing ring 5 is directly connected. A hand-operated nut 16 is threaded upon the exterior of the bushing or sleeve 10 and a shoulder 16' on this nut engages 40 or is engaged by a bearing member 17 and collar 18. The collar 18 is secured to a hub 19 of the intermediate carrier 11 and this hub is revolvably mounted on the bearing 45 member 17 that is on the sleeve or bushing 50 10. If the bushing or sleeve 10 is considered as a part of the inner carrier 9, as it may be, then the intermediate carrier 11 may be considered to be revolvably mounted 55 on said inner carrier 9. If, however, the member 9 is to be considered an adjustable part of or on the outer carrier 2 then the intermediate carrier 11 might be considered to be revolvably mounted upon a central 60 hollow portion of the outer carrier. A shaft 20 is carried in bearings 21 and 22 that are on the outer carrier 2 and at the lower end of this shaft 20 there is secured a pinion or gear 23 which drives the intermediate 65 carrier 11 through the medium of a gear 24

on said intermediate carrier 11. The bearings 21 and 22 are shown as anti-frictional radial bearings, but any suitable bearing could be employed at this place. The shaft 20 is driven in any suitable manner as by 70 belting 25 which engages the pulley 26 that is keyed to the shaft 20.

It will therefore be seen that the intermediate carrier 11 and ball-pressing ring 5 secured thereto can be continuously rotated 75 due to the driving arrangement thus described, and the carrier can be positioned as desired by means of the hand-operated nut or wheel 16 that is threaded on the exterior of the bushing or sleeve 10. A protecting guard 2^a is on the outer carrier 2 and this guard has a depending apron 2^b which extends downwardly past the lower edge of the teeth of the gear 24. The bushing or sleeve 10 can be positioned vertically, 80 as will hereinafter appear, by means of nuts 27 and 28. These nuts are shown as being screwed upon the exterior bushing or sleeve 10 and they have opposing tapering faces 27' and 28' which respectively engage the 85 beveled faces 27'' and 28'' of the outer carrier 2. Due to this tapering of the nuts the bushing or sleeve 10 can be readily secured in a fixed adjusted position. This bushing or sleeve extends downwardly 90 whereby it can guide, press and support the lower end of the spindle or shaft 8. The lower exterior portion of the spindle 8 has a tapering bevel portion 29 which engages a beveled portion 30 at the lower end of the bushing or sleeve 10 and the upper end of the spindle or shaft 8 is threaded at 31 so as to receive a nut or hand-wheel 32. The nut or hand-wheel 32 has a tapered portion 33 which engages a beveled portion 34 100 at the upper end of the bushing or sleeve, and due to the construction just described the spindle or shaft 8 can be firmly clamped in an elevated position so as to rigidly hold the inner segment ring 4 in its normal elevated operative position. If for any reason 105 it is desired to adjust the inner ring 4 so that it will be in its correct or normal operative position this adjustment can be taken care of by means of the nuts 27 and 28 above 110 described.

In the operation of the machine shown, particularly to discharge the balls after they have been ground, it is advisable to lower the abrading-wheel 7 and the inner segment 115 ring 4, as will hereinafter appear. However, after each operation of lowering the inner segment ring 4 it is advisable to have the segment ring restored to exactly the position which it occupied during the previous grinding operation. In other words, this inner segment ring 4 should not be rotated relatively to its companion segment ring. In order to assure the return of the segment ring to the same position which it previously 130

occupied there is provided guiding members, to wit, pins 35, which extend from the spindle or shaft 8 into the bushing or spindle 10. The lowering and subsequent raising of 5 the spindle or shaft 8 and the segment ring 4 connected thereto are accomplished by turning the hand-wheel 32 in one direction to effect the lowering and by turning the hand-wheel 32 in the opposite direction to 10 effect the raising. Of course the hand-wheel 32 must be turned tight enough so that in the elevated position the segment ring 4 will be secured in place.

The abrading-wheel 7 is carried on a head 15 36 that is keyed to the upper end of a shaft 37 which is mounted in bearings 38 and 39 that are on a vertically movable frame 40. This frame 40 is slidably mounted on a vertically extending guideway member 41 which 20 is on the main frame 1 and by raising and lowering the movable frame 40 the abrading-wheel 7 can be raised to operative position and subsequently moved from operative position. The bearings 38 and 39 are, of course, 25 constructed so as to properly take care of any radial thrust as well as any longitudinal thrust resulting from the performing of the grinding operation. A counter-weight 42 is connected to the movable frame 40 by means 30 of a cable or flexible connector 43 which passes over an idler-pulley 44 that is mounted on the main frame 1. A rack 45 is secured at 46 to the movable frame 40 and the upper end of this rack is engaged by a pinion or 35 segment member 47. This pinion or segment member 47 is mounted on a shaft 48 that is carried in suitable bearings on the main frame 1 and to this shaft there is keyed or otherwise secured a hand-lever 49 which can 40 be relied upon to effect a quick raising and lowering of the movable frame 40. This may be considered to constitute means for providing a rough or coarse adjustment.

In the grinding of balls it is necessary that 45 the abrading-wheel be positioned or fed with a nicety of adjustment and this is accomplished by adding to the mechanism which comprises the pinion or segment 47 and the shaft 48 a worm-wheel 50 and worm 51, the latter of which can be positioned by hand. The worm-wheel 50 is not directly connected to the shaft 48 but can be indirectly connected to said shaft by locking means 52 for locking, when desired, the worm-wheel 50 55 and the hand-lever 49 so that they cannot move relatively to each other and so that they will move together. The worm 51 is carried on a shaft 53 which is mounted on a bearing 54 that is secured to the main frame 60 1 and is operated by means of a handle 55 on the shaft 53.

The locking means 52 for in effect securing the worm-wheel 50 to the lever 49 comprises a notched plate 56 which is directly connected to the worm-wheel 50. A movable

locking member or latch 57 normally extends into a notch 58 in this plate 56, being pressed into this position by means of a spring 59. The locking member or latch 57 can be retracted whereby it will disengage the plate 70 56 by the operator forcing a handle 60 toward a handle 61 the latter of which is on the lever. It will therefore be seen that the lever 49 can be relied upon to lower the abrading-wheel from operative position and 75 to restore the abrading-wheel to practically its final position when the locking mechanism 52 is rendered inoperative by causing the latch 57 to disengage the plate 56. When, however, the abrading-wheel 7 is 80 practically in its normal position it can be fed or adjusted through the medium of the worm 51 and worm-wheel 50 provided the locking means is positioned whereby the worm-wheel 50 is locked to the lever 49, or 85 in other words indirectly connected to the shaft.

It will be manifest that instead of making the entire frame 40 movable vertically the same end could be accomplished by constructing the shaft 37 so that it could move vertically relative to a frame in which it is revolvably mounted. With such a construction counter-weighting means is preferably applied so as to lift or partially lift the 90 shaft and the abrading-wheel thereby, and the adjusting mechanism should be constructed so as to be applied to some vertically movable member which would control the position of the shaft, or which would 95 ultimately control the position of the abrading-wheel. Broadly speaking, the connection of the rack 45 to the frame may be considered as a connection made to some vertical movable member which controls the 100 position of the wheel and the vertical movable members which carry it. The counter-weight is applied so as to impart a lifting force on a member-frame 40 which controls the 105 position of the shaft 37 and abrading 110 wheel carried by it. On the main frame 1 there is mounted a pair of idler-guide pulleys 61 one of which delivers a belt 62 in a certain definite or comparatively fixed position to a pulley 63 and the other of which 115 receives the belt from said pulley 63. The pulley 63 has a cylindrical face keyed on the shaft 37 and is moving vertically relative to the belt 62 which is delivered to the pulley in practically one position only. This 120 belting serves to drive the abrading-wheel 7 in any vertical position in which it may be located, as will be manifest from an inspection of Fig. 1. In this figure it will also be noted that the axis about which the tubular 125 abrading wheel 7 revolves is eccentric or offset with respect to the axis of rotation of the ball-pressing ring—the latter of which is concentric with the ball seats of the spaced segment rings. This arrangement of the 130

tubular abrading wheel enables the operative face thereof to be employed for its full width.

The positions which the spaced segment rings, the ball-pressing ring and the abrading-wheel 7 can assume relative to each other at different times and for different purposes are illustrated in Figs. 2 to 6 inclusive. In each of these figures the outer segment ring 10 is designated by 3, the inner segment ring by 4, the ball-pressing ring by 5, and the abrading-wheel by 7. In Fig. 2, 6 indicates a row of balls which have been ground and are ready to be ejected or delivered from the machine and 6' designates a new lot of balls which are arranged in a row preparatory to being placed in the machine for grinding. In Fig. 3, the balls 6 and 6' are shown remaining in the position which they 15 occupy in Fig. 2 but the abrading-wheel 7 has been lowered preparatory to lowering the inner segment ring 4 whereby the row of balls 6 will be delivered from the machine. When the abrading-wheel 7 is in the 20 position shown in Fig. 3 a pan P is placed on the top of the abrading-wheel in the space between the abrading-wheel and the segment rings and the inner spaced segment ring 4 is lowered—by turning the hand-wheel or nut 32 (see Fig. 1)—so as to drop the inner segment ring 4, as in the position shown in Fig. 4. This allows the balls 6 to drop into the pan P as is indicated in Fig. 4 and thereafter the spaced segment 25 ring 4 is raised to the position shown in Fig. 5 and this is followed by a raising of the pressing ring 5 to the position shown in Fig. 6.

According to Fig. 5 the abrading-wheel 40 7 is shown as being raised before the pressing-ring is raised, but manifestly the abrading-wheel 7 need not be raised until after the balls to be ground occupy the position of the balls shown in Fig. 2. When the 45 balls to be ground are resting upon the spaced segment rings 3 and 4 the ball-pressing ring 5 is moved downwardly so as to press the balls against the seats on said spaced segment rings and the abrading-wheel 7 is placed in operative position relative to the spaced segment rings 3 and 4, if not already in the desired position. Such adjustment as is required can be given the abrading-wheel 7 due to the worm and worm-wheel construction heretofore described.

The grinding operation can now proceed and continue until the balls 6 have been brought to size after which the cycle of 60 operations above described can be repeated. The rings 3 and 4 have been referred to as ball-supporting or ball segment rings. They have been referred to as segment rings because frequently in the manufacture of these 65 rings it has been found advisable to have

the wearing portions thereof made of segments of hardened steel secured to the larger rings carrying the same. It is to be understood, however, that the expression "segment ring" is not to be construed as limiting these 70 ball-supporting rings to a construction in which segments are necessarily employed to provide the raceways for the balls. It is quite important that these segment rings be properly positioned relative to each other 75 and in order to provide for any inequalities or inaccuracies, due to workmanship, warping of the metals, or otherwise, a dutchman construction is provided at 3' between the segment ring 3 and the carrier therefor 80 and at 4' between the inner segment ring 4 and the carrier therefor.

In the machine shown no means for automatically feeding balls to the grinding space is shown and no means for automatically 85 delivering the balls from the grinding space is shown. It is not difficult, however, to provide a construction for this purpose and the invention herein described is applicable to a machine in which there are employed 90 means for automatically feeding, and for automatically discharging balls from the machine whereby the grinding operation may be continued; in other words, in which balls can be fed into the machine during 95 the grinding operation while simultaneously therewith other balls are being conveyed from the machine. Apparatus for automatically conveying balls to and from the ball-grinding machines in the manner just referred to is old and well known in the art. 100

The means which comprises the adjustable bushing or sleeve 10 can be employed as a means for effecting a fine or nice adjustment so that should for any reason the 105 spindle or shaft 8 be moved relatively thereto the latter can be properly positioned by merely turning a nut when it is desired to restore the shaft 8 to its normal position. This construction has its advantage even in 110 a machine where the feeding is continuous as well as in a machine which is operated as, for example, by the method illustrated in Figs. 2 to 6 inclusive. The vertical movement of the movable frame 40 is also useful where the feeding is continuous in that it allows abrading-wheels of different depths to be employed and allows of the employment of practically the full depth of an 115 abrading-wheel.

The improvements herein set forth are not limited to the precise construction and arrangement shown for they may be embodied in various forms and modifications without departing from the spirit and scope 120 of the invention.

What I claim and desire to secure by Letters Patent of the United States is:

1. A machine of the class described comprising in combination a main frame sup- 130

porting thereupon an outer carrier, an outer segment ring secured to said carrier, an inner carrier adjustably mounted on said outer carrier, an inner segment ring secured to said inner carrier, a ball-pressing ring, an intermediate carrier to which said ball-pressing ring is connected and which intermediate carrier is revolvably mounted on said inner carrier, a shaft carried in bearings on said outer carrier and having a gear meshing with a gear on said intermediate carrier for rotating the latter, and a rotatable abrading-wheel arranged to engage balls which are held in operative position on the segment rings by the pressing ring.

2. A machine of the class described comprising in combination an upright main frame, an outer carrier supporting at its lower end a ball-supporting or segment ring, an inner carrier comprising a bushing or sleeve which can be securely held in an adjusted position in the outer carrier, a spindle or shaft which can be fixedly secured in elevated position in said bushing or sleeve, an inner ball-supporting or segment ring secured to the lower end of said spindle, an intermediate carrier revolvably mounted on said bushing or sleeve, a ball-pressing ring which is revolvble by said intermediate carrier and arranged to press downwardly upon balls supported by or on said segment rings which last-mentioned rings have spaces between them through which the balls extend when thus pressed, and a revolvble abrading-wheel arranged to engage the balls thus pressed.

3. A machine of the class described having a revolvble abrading-wheel, spaced inner and outer segment rings and a revolvble ball-pressing ring, and in combination therewith an outer carrier to which the outer segment ring is secured, a bushing adjustably mounted in said carrier, means for securing said bushing in a fixed adjusted position, a spindle or shaft extending through said bushing and having connected to the lower end thereof the inner segment ring, and means for securing said shaft in a normal elevated position while a grinding operation is being performed, the construction being such that said shaft or spindle can be lowered from said normal elevated position and so that the abrading wheel can be raised and lowered.

4. A machine of the class described comprising in combination an outer carrier having at the lower end thereof means for supporting an outer segment ring, a bushing or sleeve, means for securing said bushing or sleeve in adjusted position on said outer carrier, a central spindle or shaft having secured at the lower end thereof an inner segment ring, means for securing said central spindle in adjusted position on said bushing or sleeve, which is spaced from the

outer segment ring, a ball-pressing ring and a revolvble intermediate carrier therefor, which intermediate carrier is revolvably mounted on said bushing or sleeve and is adjustable along said bushing or sleeve, the construction being such that the inner spaced segment ring can be lowered while the outer spaced segment ring and the intermediate carrier for the ball-pressing ring remain in place, the construction also being such that the abrading-wheel can be lowered from operative position and restored to operative position.

5. A machine of the class described comprising in combination inner and outer spaced segment rings, a ball-pressing ring located above said segment rings and associated therewith, a vertically movable tubular abrading-wheel located below said segment rings which tubular abrading-wheel is eccentric to the ball-pressing ring whereby the entire surface of the abrading-wheel may be utilized, an outer carrier to the lower end of which the outer of said spaced segment rings is secured, an adjustable bushing or sleeve secured in place in said outer carrier, an intermediate carrier revolvably mounted upon said bushing or sleeve for revolving said ball-pressing ring, means engaging said bushing or sleeve for positioning the intermediate carrier along the bushing or sleeve, a vertically movable spindle or shaft, means for securing said spindle or shaft in an elevated position to said bushing or sleeve, the inner of said spaced segment rings being secured to the lower end of said spindle or shaft and in normal operative position in respect to said outer ring and ball-pressing ring when said shaft is secured in said elevated position, guiding means between said sleeve and said spindle or shaft, the construction being such that said spindle or shaft and the spaced segment ring carried thereby can be lowered from its normal position, said guiding means between said spindle or shaft and said bushing or sleeve serving to maintain the spindle or shaft in proper position relative to the bushing or sleeve while said spindle or shaft is being raised or lowered.

6. A ball grinding machine of the class described comprising in combination a vertically extending main frame, an outer carrier on said main frame, an outer segment ring secured to said carrier, a bushing or sleeve passing through a vertically extending central opening in said carrier and held in place by a pair of opposing nuts on the sleeve and which nuts each have a wedging engagement with the outer carrier whereby said bushing or sleeve can be securely held in an adjusted position on said outer carrier, said bushing or sleeve also having at each end thereof tapering faces, a spindle or shaft extending through said bushing or

6

sleeve and having secured to the lower end thereof an inner segment ring which is spaced from said outer segment ring and which is arranged so as to coöperate therewith, said spindle or shaft having at the lower portion thereof a beveled face which engages the tapering face at the lower end of the sleeve and a nut on the upper end of said shaft which nut has a tapering face 5 that engages the tapering face at the upper end of said sleeve whereby said nut can securely clamp said spindle or shaft in a fixed position in said sleeve or bushing, an intermediate carrier revolubly mounted upon 10 said sleeve or bushing and a nut engaging the exterior of said sleeve or bushing for positioning the carrier along said sleeve or bushing, a ball-pressing ring connected to said intermediate carrier, a tubular abrading-wheel located below said spaced segment rings and carried on a shaft which is in bearings that are on a frame which is slidably mounted on the main frame whereby the abrading-wheel can be raised and 15 lowered relatively to the outer spaced segment ring, means comprising a counter-weight for counter-balancing said movable frame and parts carried thereby, and means for effecting a raising and lowering of said 20 movable frame and for holding said frame in adjusted position.

7. A machine of the class described comprising in combination a main frame supporting thereupon an outer carrier, an outer 35 segment ring secured to said carrier, an inner carrier adjustably mounted on said outer carrier, means for securing said inner carrier in adjusted position on said outer carrier, an inner segment ring secured to 40 said inner carrier, a ball pressing ring, an intermediate carrier to which said ball pressing ring is connected, which intermediate carrier is revolubly mounted on said inner carrier and is adjustable along said inner carrier, and a rotatable abrading-wheel 45 arranged to engage balls when the latter are in operative position on said segment rings.

8. A machine of the class described comprising in combination an upright main 50 frame, an outer carrier supporting at its lower end a ball supporting or segment ring, an inner carrier comprising a bushing or sleeve which can be adjustably positioned in the outer carrier, means for clamping 55 said bushing or sleeve to said outer carrier, a vertically adjustable spindle or shaft extending into said bushing or sleeve, means for clamping said spindle or shaft to said bushing or sleeve, an inner ball supporting 60 or segment ring secured to the lower end of said spindle, an intermediate carrier revolubly mounted on said bushing or sleeve, a ball pressing ring connected to said intermediate carrier and arranged to press downwardly upon balls supported by or on said 65

segment rings, which last mentioned rings have spaces between them through which the balls extend when thus pressed, and a revoluble abrading-wheel arranged to engage the balls thus pressed.

9. A ball grinding machine of the class described comprising in combination spaced segment or ball-supporting rings which are relatively stationary when a grinding operation is being performed but which are 70 mounted so that one of the segment rings can be moved vertically relative to its companion ring, a ball-revolving ring arranged to press balls downwardly on the seats of said segment rings during a grinding operation, the construction being such that said ball-pressing ring can be raised relatively to said ball-supporting rings, an abrading-wheel having the axis of rotation eccentric relative to the center of the ball seats on said 75 spaced segment rings, and means for raising and lowering the abrading-wheel, a rack connected to a vertically movable member upon which the abrading-wheel is carried, a fixed but rotatable shaft, a pinion or gear 80 secured to said shaft and engaging said rack, a worm-wheel revolubly mounted on said shaft and a hand-operated worm for turning said worm-wheel, a lever secured to said shaft for turning it, and means for 85 locking the worm-wheel to the lever when 90 desired.

10. A machine of the class described comprising in combination a main frame, carriers to which there are secured ball-supporting rings and a ball-pressing ring, and associated with said rings an abrading-wheel that is located below said ball-supporting rings, which abrading-wheel is mounted on a shaft having a vertically extending axis and so that the abrading-wheel can be raised and lowered, means for counter-balancing the weight of the abrading-wheel and the vertically movable parts upon which the same is supported, and a 100 rack connected to one of the vertically movable parts which rack is actuated through the medium of a gear carried on a shaft which is mounted in the main frame, said shaft having associated therewith a worm 105 and worm-wheel for effecting a fine adjustment and a hand-operated lever for effecting a coarse adjustment.

11. A machine of the class described comprising in combination spaced segment 110 rings, a ball-pressing ring located at one side of said spaced segment rings, an abrading-wheel located at the other side of said spaced segment rings, means comprising one set of members for effecting a fine adjustment of the abrading-wheel relative to the spaced segment rings and another set of members for effecting a coarse adjustment 115 of the abrading-wheel relative to said ball segment rings.

12. A machine of the class described comprising in combination spaced segment rings, a ball-pressing ring above said spaced segment rings, an abrading-wheel below said spaced segment rings, means for causing one of the spaced segment rings to be moved downwardly relative to the other spaced segment ring and for securing said vertically movable spaced segment ring in an elevated operative position, and means for raising and lowering said abrading-wheel, said last-mentioned means comprising members for effecting a quick raising and lowering of the abrading-wheel to and from operative position and also comprising members for effecting a slow fine adjustment when the abrading-wheel is in operative position.

13. A machine of the class described comprising in combination spaced segment rings, at least one of which is vertically movable relative to the other, a vertically movable ball-revolving ring for pressing balls downwardly against seats on said spaced segment rings when the latter are in operative position relative to each other, a vertically movable abrading-wheel located below said spaced segment rings, and means for raising and lowering said abrading-wheel said means comprising members one of which is a hand-operated lever for effecting an extended, quick, vertical movement of the abrading-wheel, said means also comprising a worm-wheel and hand-operated worm for effecting a slow, fine adjustment.

14. A machine of the class described comprising in combination spaced segment rings, at least one of which is vertically movable relative to the other, a vertically movable ball-revolving ring for pressing balls downwardly against seats on said spaced segment rings when the latter are in operative position relative to each other, a vertically movable abrading-wheel located below said spaced segment rings, means for raising and lowering said abrading-wheel said means comprising members one of which is a hand-operated lever for effecting an extended, quick, vertical movement of the abrading-wheel, said means also comprising a worm-wheel and hand-operated worm for effecting a slow, fine adjustment, and a weight arranged to counter-balance at least a part of the weight of the abrading-wheel and the movable parts carrying the same.

15. A machine of the class described comprising in combination a main frame, spaced inner and outer segment rings, carriers for said spaced segment rings, which carriers are supported by said frame, a ball-pressing ring and rotatable carrier therefor, means for rotating said last-mentioned carrier, an abrading-wheel arranged to coöperate with said spaced segment rings and said ball-

pressing, a vertically movable shaft carrying a vertically movable pulley secured to said shaft, and belting traveling in a fixed path, the construction being such that the pulley can be moved vertically relative to that portion of the belting which engages the same.

16. A machine of the class described comprising in combination an upright main frame carrying at the upper end thereof an outer carrier supporting at the lower end thereof an outer ball-supporting or segment ring, an inner carrier supporting at the lower end thereof an inner ball-supporting segment ring which is spaced from the outer ball-supporting or segment ring, an intermediate revoluble carrier mounted on one of the segment ring carriers, and means engaging one of said segment ring carriers for positioning said intermediate carrier, a ball-pressing ring connected to said intermediate carrier, an abrading-wheel located below said segment rings, a frame slidably mounted on a vertically extending guideway on the main frame, a shaft mounted in bearings in said movable frame and carrying the abrading-wheel at the upper end of the shaft, and means carried by said main frame and secured to said movable frame for effecting adjustment of the latter.

17. A ball grinding machine of the class described comprising in combination a vertically extending main frame, an outer carrier on said main frame, an outer segment ring secured to said carrier, a bushing or sleeve passing through a vertically extending opening in said carrier and held in place by a pair of opposing nuts on the sleeve, a spindle or shaft extending through said bushing or sleeve and having secured to the lower end thereof an inner segment ring which is spaced from said outer segment ring and which inner segment ring is arranged so as to coöperate with the outer segment ring, said spindle or shaft having at the lower portion thereof a face which engages the lower end of the sleeve, a nut on the upper end of said shaft, which nut has a face that engages the upper end of said sleeve whereby said nut can securely clamp said spindle or shaft in a fixed position in said sleeve or bushing, an intermediate carrier revolubly mounted upon said sleeve or bushing, a nut engaging the exterior of said sleeve or bushing for positioning the intermediate carrier along said sleeve or bushing, a ball-pressing ring connected to said intermediate carrier, and a vertically adjustable tubular abrading wheel located below said spaced segment rings.

18. A machine of the class described comprising in combination a frame, a carrier comprising a bushing or sleeve, means for securing said bushing or sleeve in adjusted position on said frame, a spindle or shaft

- carrying a segment ring which spindle or shaft is carried by said bushing or sleeve, a second carrier carried by said bushing or sleeve, which second carrier has secured to it a ball ring, means between said second carrier and said sleeve whereby said second carrier can be positioned along said bushing or sleeve, and an abrading-wheel operatively associated with said rings.
- 10 19. A machine of the class described comprising in combination a frame, a bushing or sleeve, means for maintaining the bushing or sleeve in position on the frame, a spindle or shaft extending into said bushing or sleeve, a segment ring carried by said

spindle or shaft, a second carrier, which second carrier is revolvably mounted on said bushing or sleeve, means between said second carrier and said bushing or sleeve for positioning the second carrier along said bushing or sleeve, a ball ring secured to said second carrier and an abrading-wheel operatively associated with said rings.

This specification signed and witnessed this 24th day of May, A. D. 1917. 25

OTTO W. SCHAUM.
